UNITED STATES PATENT OFFICE.

MARTIN M. HILL, OF ST. MARYS, PENNSYLVANIA.

DESIGN FOR A KITCHEN UTENSIL.

48,973.

Specification for Design.

Patented May 2, 1916.

Application filed March 12, 1915. Serial No. 13,965. Term of patent 7 years.

To all whom it may concern:

Be it known that I, MARTIN M. HILL, a citizen of the United States, residing at St. Marys, in the county of Elk and State of Pennsylvania, have invented a new, original, and ornamental Design for Kitchen Utensils, of which the following is a specification, reference being had to the accompanying drawing, forming a part thereof.

The figure is a perspective view of a kitchen utensil, showing my new design.

I claim:

The ornamental design for a kitchen utensil, as shown.

MARTIN M. HILL.

Witnesses:

JOHN B. FORSTER,
GEORG BEIMEL.
